UNITED STATES PATENT OFFICE.

HENRY BERG, OF DAVENPORT, IOWA.

IMPROVEMENT IN BREECH-LOADING FIRE-ARMS.

Specification forming part of Letters Patent No. 34,729, dated March 25, 1862.

To all whom it may concern:

Be it known that I, HENRY BERG, of Davenport, in the county of Scott and State of Iowa, have invented a certain new and useful Improvement in Breech-Loading Guns; and I hereby declare the following to be a full and exact description of the same, reference being had to the accompanying drawings, making part of this specification, in which—

Figure 1 is a side elevation of a carbine illustrating my invention. Fig. 2 is a vertical section of the same. Fig. 3 is a longitudinal section of the same.

Similar letters of reference indicate corresponding parts in the several figures.

The nature of my invention consists, first, in an improved mode of attaching and operating a sliding pivoted barrel; second, in devices by which the motion of the barrel is made to cock and prime the pieces, as hereinafter explained; third, in a device for disconnecting the self-cocking apparatus; fourth, in a device for permitting the withdrawal of the priming.

To enable others skilled in the art so make and use my invention, I will proceed to describe its construction and operation.

A represents the stock, and B the breech, which are rigidly connected together.

C' are movable face-plates covering the lock on each side.

D is the barrel, provided with arms d d', by means of which it is pivoted to the breech.

E is a horizontal bolt passing through a slot in the breech, which slot is narrow horizontally, so as to confine the bolt endwise of the gun, but wide vertically, to allow play to the bolt in that direction.

e e' are flanges formed upon the bolt E near its respective ends, and fitting in eyes in the ends of the arms d d'. The said flanges being eccentric to that portion of the bolt which fits within the slot of the breech, a rotation of the bolt will move the barrel forward or backward. This rotation is effected by means of a lever or crank, F.

f is a spring-catch, which retains the lever F in either position. The front of the breech is formed with a circular flange, b, fitting in a corresponding annular groove or socket in the rear of the barrel, in order to form a tight joint when the barrel is drawn back into position for firing.

The main portions of the lock, being of common construction, require no specific description. The hammer H is also of common construction, but is provided with a stud or pin, h, projecting horizontally from it, for the purpose of raising it by the action of the barrel, as will be presently explained.

I is a lever slotted to receive a bolt or screw, i, by means of which the lever is fulcrumed to the face-plate C'.

J is a spring pressing against the end of the lever I, to hold it in a forward position. The slot in the said lever permits it to be forced backward.

K is a catch taking into a notch in the lever I, to hold it in a forward position when desired.

i' i' are short arms projecting horizontally from the forward end of the lever I.

Fig. 4 is a separate view of the inside of the face-plate C', with the lever I, spring J, and catch K attached. The retracted position of the lever is here shown in black lines, and the forward or operating position in red.

G is a chamber to contain tape-priming, (represented by yellow lines,) which extends up through a passage, M, to the nipple N.

L is a feed-band pivoted to the lower part of the hammer-stock and employed to forward the priming up the passage M at every elevation of the hammer.

m is a cutter upon the hammer, which severs a suitable piece of the priming at each stroke.

O is an adjustable elastic plate fitting over the orifice of the passage M, but movable, so as to permit the withdrawal of the priming when desired.

In Fig. 2 parts in front of the line of section are indicated by full red lines, and parts at back hidden from view are shown in dotted black lines.

The above-described improvements are of great value in carbines for mounted service, but are applicable also to other arms.

The manner of using the arm is as follows: The parts being in the position shown in Figs. 2 and 3, (which is the position for firing,) if it be desired to load the piece, the finger and thumb are applied to the pin f' of the crank-lever F, and the catch f at the same time retracted by a slight pressure. The lever is then drawn up and over to the position shown in Fig. 3, which, by the action of the eccentrics e e', throws the barrel forward, as shown by

ted lines in Fig. 3. The barrel is then thrown to a position at right angles with the breech, the latter being held in a vertical position to receive the charge, while the barrel projects over the shoulder of the operator. The charge being inserted in the breech, the latter (with the stock to which it is attached) is restored to a horizontal position, and the barrel falls by its own weight to a line with the breech, in the position shown in red in Fig. 3. This descent of the barrel raises the hammer to full-cock by a horn or shoulder at the rear end of the arm d' , engaging beneath the arm i' of the lever I, and the arm i'' , engaging beneath the pin h of the hammer. At the same time the feed-band L, being, by the motion of the hammer, driven up the passage M, carries forward the tape-primer, causing it to project over the nipple. This position of the hammer and primer apparatus is shown by dotted red lines in Fig. 2. The crank-lever F being now restored to its forward position, the barrel is thereby drawn back, and the piece is in readiness for firing.

It will be observed that as the barrel is elevated the spring J permits the lever I to recede sufficiently to allow the passage of the horn or shoulder by which the lever is to be elevated. It will further be seen that as the barrel is drawn backward into position for firing, the end of the arm d' , pressing against the front end of the lever, forces it to its extreme backward position, and so holds it. While

the lever I is in this position, by applying the thumb-nail to a pin, k , projecting from the forward end of the catch K through the face-plate C' to the exterior, the rear end of the said catch may be thrown up into the notch in the lever I, so as to hold the lever in its retracted position. While the lever is thus held the motion of the barrel is not communicated to the hammer or primer. By relaxing the screw o the plate O may be slipped back and the primer withdrawn.

Having thus described my invention, what I claim as new therein, and desire to secure by Letters Patent, is—

1. The crank-lever F f and eccentrically-flanged bolt E $e' e'$, constructed as described, and employed in connection with the hinged barrel D $d' d'$ and vertically-slotted breech B, in the manner and for the purposes explained.
2. The yielding lever I $i' i''$, constructed and employed in the manner explained, to raise the hammer by the depression of the barrel.
3. The catch K k , employed in the described connection with the sliding lever I, to disconnect the self-cocking apparatus.
4. The sliding plate O, employed in the manner shown and explained, to cover the primer-passage M or permit the withdrawal of the primer when desired.

HENRY BERG.
